(57) **CLAIM**

The ornamental design for a modular video wall, as shown and described.

DESCRIPTION

FIG. 1 is a front and side perspective view of a panoramic modular video wall in accordance with the present design, with six display screens arranged in two rows and on-screen cameras positioned between the display screens, mounted to the edges, illustrating a person standing in front of the modular video wall;

FIG. 2 is a blown-up perspective view of at least one on-screen camera illustrated in FIG. 1, illustrating the camera of FIG. 1 mounted to the edges of two display screens that are arranged side-by-side; and,

FIG. 3 is a front and side perspective view of a panoramic modular video wall in accordance with another embodiment of the present design, scaled for a one-to-one projection display, illustrating two equidistant on-screen cameras positioned within the display screen and a projector positioned in between the two on-screen cameras.

The illustrations in the drawings that are shown in broken lines are environment structure that is not part of the design.
